2 Claims

ABSTRACT OF THE DISCLOSURE

Fixture for detachably mounting toilet seat on toilet bowl without the use of tools, firmly holding the seat in position and enabling removal of the seat by lifting the seat and the hinge pin for the seat and post parts of the fixture. The fixture includes two socket members extending through the back part of the toilet bowl and secured thereto as by nuts, and posts for the hinge pins, each post having a locking pin depending therefrom within the socket of the socket member and camming the socket member to be locked thereto by pressing each post and pin downwardly along its socket. A detent locking connection is provided between the socket and pin. The posts, pins and sockets are made from a suitable thermoplastic material having good memory qualities, to assure a snap gripping action of the detent locking connection as the pins are inserted into and withdrawn from the sockets.

BACKGROUND OF INVENTION

This application is a continuation-in-part of my application Ser. No. 659,488, filed Aug. 9, 1967, now abandoned.

SUMMARY OF THE INVENTION AND OBJECTS

Simple snap action locking pin and socket connection for the hinge pin for a toilet seat, retaining seat to a toilet bowl for ready removal and replacement, and held in position by a snap action detent connection maintained by the material from which the locking pin and socket are made.

A principal object of the present invention is to provide a simple snap action pin and socket connection for detachably retaining a toilet seat to a toilet bowl and accommodating ready removal of the seat for cleaning.

Another object of the invention is to provide a removable toilet seat and cover for toilet bowls, including fixtures forming mountings for the pivots for the toilet seat, made from a thermoplastic material having memory qualities, retained in firm position on the bowl by a snap action detent connection, and readily removable by pulling upwardly on the toilet seat.

Another object of the invention is to provide a fixture for the hinge pin for a toilet seat made from a plastic material and retained to the toilet bowl without the use of the washers heretofore required, and removable by a simple upward pulling action on the toilet seat, without the use of the usual tools.

Still another object of the invention is to provide an economical mounting for the hinge pin for a toilet seat enabling replacement and removal of the seat by a straight downward or upward pulling action on the seat, in which the seat is firmly held to the bowl by a snap action connection.

Other objects, features and advantages of the invention will be readily apparent from the following description of a preferred embodiment thereof, taken in conjunction with the accompanying drawings although variations and

2

modifications may be effected without departing from the spirit and scope of the novel concepts of the disclosure.

DESCRIPTION OF THE DRAWINGS

5 FIG. 1 is a top plan view of a toilet bowl having a toilet seat and lid hingedly retained to the bowl by a seat retaining fixture constructed in accordance with the principles of the present invention.

10 FIG. 2 is an exploded view of a fixture for one end of a hinge pin for the toilet seat constructed in accordance with the principles of the present invention, with the socket member in section and shown as extending through the mounting flange for the toilet seat; and

15 FIG. 3 is a sectional view taken through one of the hinge pin fixtures, substantially along line III—III of FIG. 1.

DESCRIPTION OF PREFERRED EMBODIMENT OF INVENTION

In the embodiment of the invention illustrated in the drawings, I have generally shown in FIG. 1 a toilet bowl 10 having a reduced area rear seat mounting position 11 extending to the conventional tank 12. I have also shown a toilet seat and cover indicated generally by reference character 13 of a conventional form and including a seat 15 having a reduced width back portion having spaced ears 16, 16 extending rearwardly therefrom and forming a means for attaching the seat to the toilet bowl by a hinge pin 17. Said hinge pin extends through said ears and beyond opposite sides thereof and also may form a mounting for a reduced width rear portion 19 extending rearwardly of a lid 21 for the toilet seat. The toilet seat 15, lid 21 and reduced width rear portion 19, and hinge pin 17 may be of various conventional forms so need not herein be shown or described further. The seat may or may not have a lid, depending upon the location of the toilet bowl.

35 Referring now in particular to the detachable mounting for opposite ends of the hinge pin 17, hinging the seat and cover to the toilet bowl 10, an individual upright toilet seat hinge mounting post 22 is provided to form a mounting for each end of the hinge pin 17. The post 22 has a retainer pin 23 depending therefrom and adapted to be carried in a socket 25 having a cylindrically shaped sidewall of a socket member 35, extending through the reduced width mounting portion 11 of the toilet bowl and secured thereto as by a nut 26.

40 The post 22 is shown in FIGS. 2 and 3 as having flat top and bottom walls 27 and as having a generally cylindrical wall portion 28 extending between said walls. The cylindrical wall portion 28 is cut away for a portion of its length to provide an inwardly facing plane vertical face 29, terminating at its lower end into a downwardly sloping beveled face 30 extending to the cylindrical wall of said post a short distance above the bottom wall 27. The retainer pin 23 is shown as being formed integrally with the post 22 and extending downwardly from the bottom wall 27 thereof in axially aligned relation with respect to the axial center of the cylindrical wall portion 28 of said post 22. The flat inwardly facing plane face 29 is shown as having a drilled hole 31 leading thereto and forming a mounting for an end of the hinge pin 17. The flat inwardly facing plane face 29 is also adapted to be abutted by the outer side of an ear 16 for the toilet seat. The post 22 and integral retainer pin 23 depending therefrom are preferably made from a plastic material having long memory retaining qualities, with some inherent lubricating qualities, accommodating ready insertion of the retainer pin 23 in the socket 25 for removal and replacement in said socket over long periods of years. A suitable plastic material is a polyethylene material, although a nylon plastic material is also a suitable material as are various other well-known forms of plastics.

45 The retainer pin 23 has a V-shaped annular groove or

2. The hinge fixture of claim 1,
 wherein the detent and groove means includes a V-shaped groove extending about each retainer pin adjacent the lower end portion thereof and each retainer pin has a conical leading end portion extending beneath said groove,
 wherein the socket member has an internal cylindrical side wall having a generally V-shaped detent projection extending inwardly of said cylindrical side wall and intersected by said at least one radial slot,
 whereby the conical leading end portions of said retainer pins engage said detent projections upon insertion of said retainer pins within said socket members and cam said detent projections outwardly to make snap engagement with said V-shaped groove extending entirely around the periphery of and girdling said retainer pins.
